UNITED STATES PATENT OFFICE.

JOHN N. WHITEHOUSE, OF NEW YORK, N. Y.

TOY.

1,063,403.

Specification of Letters Patent.

Patented June 3, 1913.

Application filed April 6, 1912. Serial No. 686,850.

To all whom it may concern:

Be it known that I, JOHN N. WHITEHOUSE, a citizen of the United States, residing at New York, in the county of New York and State of New York, have invented certain new and useful Improvements in Toys, of which the following is a specification.

My present invention relates to an improved doll or animal toy having devices therein whereby the eyes can be moved laterally—combined with other devices whereby the toy is simultaneously caused to utter sounds or cries.

15 The drawings show only one of the specific embodiments that my invention is adapted to take, and in them the invention is shown applied to a doll although, of course, it will be understood that it is also applicable to other toys such as all kinds of animals.

20 In the drawings, Figure 1 is a front elevation of a doll showing my improvements applied thereto, portion of the structure being broken away to reveal the internal structure; Fig. 2 is a sectional view on the line 2—2 of Fig. 1, looking in the direction of the arrows; and Fig. 3 is a detailed view of a modification.

25 I will now describe the specific devices of the drawings.

1 is a doll having eye openings 2.

3—3 are eyes supported on the upper ends of elongated members or wires 4, said wires 35 being crossed at 5 where they are pivotally connected, and thence extend down into the doll where a spiral spring 6 is located between their free ends to give said members 4 and their supported eyes a normal relative position to each other.

40 7 is a collapsible chamber also located between the lower ends of the members 4. This chamber consists of a pair of more or less stiff circular heads 8, to the outside of 45 which the legs of the wires 4 are secured by pieces of cloth 9 glued over the wires and against the heads 8. The previously described spiral spring 6 is supported between these heads and is retained in place 50 by having one of its ends 6^a forced into a hole in the inner surface of one of the heads. The closed collapsible chamber 7 is completed by parchment-paper or a suitable airtight fabric 10 which forms the cylindrical

wall of the chamber and is glued at its ends 55 to the heads 8.

56 11 is an air hole opening through the head 8, said opening having a lateral extension 11^a in the form of a groove located on the inner surface of the head 8.

60 12 is a thin sheet metal tongue located over the groove 11^a and 14 is a diaphragm in the form of a piece of paper glued to the inner face of the head 8 over the hole 11 and over the base of the tongue 12, the said 65 tongue 12 being secured only to the diaphragm 14. (See Fig. 2.)

66 When the sides of the doll are compressed to move the lower ends of the wires 4 and circular heads 8 toward each other against 70 the opposing action of the spiral spring 6, and similarly upon the release of these parts from said pressure, the eyes 3 of the doll are caused to move laterally and it is caused to utter cries or sounds by the passage of 75 the air past the sounding devices at the air hole opening in the head of the collapsible chamber.

76 Figure 1 shows the eyes 3 of the doll located behind the eye openings 2, whereas 80 Fig. 3 shows a modification wherein the free ends of the wires 4 project slightly through the eye openings and support the eyes 3 on the outside of the openings 2. The fact that the wires 4 are crossed at 5 decreases the 85 diameter of the device at this point to correspond with the reduced diameter or neck portion of the doll.

86 What I claim is:

1. A toy having movable eyes and containing eye-supporting members movable to and away from each other, and yielding means acting on said members to hold them at a normal position apart.

2. A toy having movable eyes and containing elongated eye-supporting members which cross each other and are there pivotally connected, and elastic means acting upon the ends of said crossed members to yieldingly hold them in a normal relative 100 position.

3. A toy having movable eyes and containing elongated eye-supporting members which cross each other and are there pivotally connected, and a spring located between 105 the ends of said members on the opposite side of their pivotal connection from the aforesaid eyes of said members.

4. A toy having movable eyes and containing elongated eye-supporting members which cross each other and are there pivotally connected, a spring located between the 5 ends of said members on the opposite side of their pivotal connection from the aforesaid eyes of said members, and a closed collapsible chamber also located between the ends of said elongated members, said chamber having an air hole opening through it,

and a valve and sounding device at said opening operative to be sounded from the passage of air at said opening.

In testimony whereof I affix my signature in presence of two witnesses.

JOHN N. WHITEHOUSE.

Witnesses:

E. W. SCHERR, Jr.,

ALAN CR. McCONNELL.
